US00D648142S

(12) **United States Design Patent**
Ferraro et al.

(10) **Patent No.:** **US D648,142 S**
(b4) **Date of Patent:** ** **Nov. 8, 2011**

(54) **HANGER PORTION**

(75) Inventors: **Brandon R. Ferraro**, St. Louis Park, MN (US); **Keith C. Cedro**, Clifton, NJ (US); **Jake Strassberger**, South Plainfield, NJ (US)

(73) Assignee: **Target Brands, Inc.**, Minneapolis, MN (US)

(**) Term: **14 Years**

(21) Appl. No.: **29/346,559**

(22) Filed: **Nov. 2, 2009**

(51) LOC (9) Cl. **06-08**

(52) U.S. Cl. **D6/328**

(58) Field of Classification Search D6/315-328,

(74) Attorney, Agent, or Firm — Griffiths & Seaton PLLC

(57) **CLAIM**

The ornamental design for a hanger portion, as shown and described.

DESCRIPTION

FIG. 1 is a front, perspective view of a hanger portion showing a first embodiment of our new design;

FIG. 2 is a rear, perspective view thereof;

FIG. 3 is a front view thereof;

FIG. 4 is a rear view thereof;

FIG. 5 is a right side view thereof;

FIG. 6 is a left side view thereof;

FIG. 7 is a top view thereof; and,

FIG. 8 is a bottom view thereof.

The broken lines indicate unclaimed portions of the design. The dash lines indicate the boundary of the claimed design. None of the broken lines and dash lines forms part of the claimed design.

1 Claim, 5 Drawing Sheets
